UNITED STATES PATENT OFFICE.

JAMES FISHER, OF NEW ORLEANS, LOUISIANA.

APPARATUS FOR FEEDING BAGASSE-FURNACES.

SPECIFICATION forming part of Letters Patent No. 564,918, dated July 28, 1896.

Application filed May 22, 1896. Serial No. 592,624. (No model.)

To all whom it may concern:

Be it known that I, JAMES FISHER, a citizen of the United States, residing at New Orleans, in the parish of Orleans and State of 5 Louisiana, have invented certain new and useful Improvements in Apparatus for Feeding Bagasse-Furnaces; and I do hereby declare the following to be a full, clear, and exact description of the invention, such as will 10 enable others skilled in the art to which it app pertains to make and use the same.

My invention relates to improvements in apparatus for feeding bagasse to furnaces, and has for its object to provide an improved 15 means for feeding the bagasse to a furnace whereby sparks are prevented from escaping from the mouth of the furnace, and the bagasse is more equally distributed over the grate-bars of the furnace than is possible with 20 the devices now most commonly in use.

My invention consists in certain novel features and arrangement of parts hereinafter described and claimed.

Reference is had to the accompanying drawings, in which the same parts are indicated by the same letters throughout the several views.

Figure 1 represents a vertical sectional view through my feeding apparatus, taken on the 30 line 1 1 of Fig. 2. Fig. 2 is a horizontal sectional view taken on the line 2 2 of Fig. 1 and shows the feeding apparatus in plan view. Fig. 3 is an enlarged detail sectional view taken on the line 3 3 of Fig. 1, parts being 35 broken away. Fig. 4 is a side view of one of the brackets for supporting the discharging-rollers and looking toward the top of the sheet in Fig. 3. Fig. 5 is a similar view to Fig. 4, showing a modification in which a lower roller is used in connection with the bladed roller; and Fig. 6 is a partial side elevation showing the feeding-rollers as driven 40 from a blast-engine instead of from the carrier.

A represents an endless carrier connected either directly or indirectly with the mill and driven by any suitable source of power. This carrier runs over the drum B, mounted rigidly upon a shaft C, journaled in suitable 45 supports M⁴. A gear-wheel c on this shaft C meshes with a gear-wheel c' on the shaft C', also journaled in the supports M⁴, and drives

the said shaft C', which latter carries a sprocket-wheel D for driving a chain E for rotating the feeding-rollers, as hereinafter 55 more fully described.

M represents an inclined chute, upon which the bagasse is discharged from the endless belt A. This chute is supported at its upper end by means of brackets m⁵, secured to supports M⁴, or in any suitable way, and at its lower end by means of brackets M', which are secured, as at m², to the front wall of the furnace, as shown in Fig. 1. This chute has side pieces M³ and a hinged portion M² in its 60 bottom. This hinged portion M² may be raised or lowered upon its hinges m³ by means of ropes m⁶, secured at one end, as at m⁴, to the hinged portion M² of the bottom of the chute and reeving over elevated pulleys O. The 65 reason for having this middle portion of the chute hinged, as shown, is to allow it to be lowered in order to permit access to the front of the boiler for cleaning out the flues when desired, or for dumping the bagasse into carts 70 if the furnace is stopped for any reason.

S represents the furnace-opening through which the bagasse is fed. There may be one opening for each furnace, if preferred, or there may be one continuous opening for all, 75 as shown.

T represents the grate-bars of the furnace, and t represents one or more doors through which the mass of fuel upon the grate T may be stirred.

t' represents one or more ash-doors which allow access beneath the furnace-grate.

U represent boilers which communicate with the common smoke-box V, surmounted with smoke-stack W. These boilers may be 80 of any well-known or desired form, and that shown is simply for the sake of illustration.

The brackets M', one being upon each side of the lower end of the chute M, have each a pair of vertical bifurcated standards m and m' bolted thereto, and journal-blocks g⁰ and g⁰ are adapted to fit into these bifurcated standards m and m', respectively, at either side of the chute, as shown most clearly in Figs. 3 and 4. A shaft G is journaled in the blocks g⁰ in the upper one m of the bifurcated standards, and works in slots h⁰ in the sides M³, and a roller H, having radial ribs or blades h and circular end disks h', is mounted 85 90 95 100

upon this shaft G. A sprocket-wheel F is mounted upon one end of the shaft G, and the sprocket-chain E, driven by the sprocket-wheel D on the shaft C', passes over said sprocket-wheel F and drives the roller H. A shaft Q is journaled in the blocks q^0 in the lower one m' of the said bifurcated standards, and a roller R, having radially-extending teeth q thereon, is mounted upon said shaft 10 and rotates therewith. The shaft Q works in slots r^0 in the side pieces M^3 in like manner as the shaft G in the slots h^0 . A sprocket-wheel Q' is provided upon one end of said shaft Q, and a sprocket-chain P, passing over this sprocket-wheel, is driven by the sprocket-wheel G' on the shaft G, and rotates the roller R in the same direction with the roller H. Coil-springs g' and q' are held between the bifurcations of the standards m and m' in 20 position to bear upon the journal-blocks g^0 and q^0 by means of plates s and s' . These springs are for the purpose of holding the rollers down against the tendency they would have to rise when a large bulk of bagasse 25 passes beneath them.

The bagasse after being discharged upon the chute M slides down to the bladed roller H, which is constantly revolving, and which feeds the bagasse along to the toothed roller 30 R. This toothed roller should be geared so as to be driven somewhat faster than the bladed roller, and tears the mass of bagasse passing beneath it to pieces, and throws it off into the furnace, distributing the same 35 evenly over the furnace-grate.

Where the furnace is to be fed through more than one opening, or where several furnaces are used with a separate opening for each furnace, partitions may be formed on 40 the chute and the rollers may be divided into sections, and intermediate brackets and bearings be provided. The sides M^3 of the chute extend up above these rollers, so that the bagasse cannot fall over therefrom, and 45 plates N, held in position by means of guides n , secured to the sides M^3 and slotted to fit over the shaft of the rollers H and R, are arranged to rest upon the shafts G and Q and rise and fall therewith in order to close the 50 slots in the sides M^3 above the said shafts.

A door K, preferably of metal, is hinged, as at k , above the opening to the furnace and projects forward and upward therefrom and rests upon lugs n' , projecting inwardly from 55 the sliding plates N. This door just fits in between the sides of the chute, and thus, being practically air-tight, prevents the escape of any sparks which might otherwise fly out from the mouth of the furnace. As the roller 60 H rises and falls, the door K will swing up or down upon its hinges, its forward end at all times resting upon the lugs n' on the plates N immediately above the blades of the said roller.

65 If desired, I may use another roller H', journaled in suitable bearings I, secured to the brackets M', immediately beneath the roller

H, and driven from said roller H by means of gears G^2 and H^2 on the shafts of the said rollers H and H', respectively, as shown in 70 Fig. 5. In this case the upper surface of the roller H' would rotate through a transverse slot in the floor of the chute M. I also may drive the feeding-rollers from a blast-engine, as shown in Fig. 6, wherein a belt x from the 75 engine X drives a pulley x' on the shaft Q of the toothed roller, which in turn drives the bladed roller H.

It will be seen that many modifications of my apparatus might be made which could be 80 used without departing from the spirit of my invention.

Having thus described my invention, what I claim, and desire to secure by Letters Patent of the United States, is—

1. In an apparatus of the character described, the combination with a furnace having an opening in the front thereof for the admission of fuel above the grate, of an inclined chute adapted to receive the bagasse at its 90 upper end from an elevated carrier and supported at said end in an elevated position by means of brackets, brackets secured to the front of the furnace and supporting the lower end of said chute, a roller having radial blades 95 mounted across the said chute near its lower end in bearings in said brackets, and means for driving said bladed roller, and a roller having radial teeth also mounted across said chute at its lower end in bearings in said 100 brackets, and gearing between said rollers for driving them in the same direction, substantially as described.

2. In an apparatus of the character described, the combination with a furnace having an opening in the front thereof for the admission of fuel, of an inclined chute adapted to receive the bagasse at its upper end from an elevated carrier and supported at 105 said end in an elevated position, brackets secured to the front of the furnace and supporting the lower end of said chute, a roller having radial blades mounted across said chute near its lower end in bearings in said brackets, and means for driving said bladed 110 roller, a second roller having radial teeth also mounted across said chute at its lower end in bearings in said brackets, gearing between said rollers for driving them in the same direction, 115 substantially as described.

3. In an apparatus of the character described, the combination with a furnace having an opening in the front thereof for the admission of fuel, of an elevated chute adapted to receive the bagasse at its upper end from an elevated carrier and supported at said end in an elevated position, brackets secured to the front of the furnace and supporting the 120 lower end of said chute; a roller having radial blades thereon mounted across the said chute near its lower end in bearings mounted in 125 said brackets and capable of vertical move-

- ment therein; means for driving said bladed roller; a second roller having radial teeth also mounted across said chute, at its lower end in vertically-movable bearings in said brackets; gearing between said rollers for driving them in the same direction; and a pivoted door secured to the front of the furnace above the fire-opening and extending over said rollers, substantially as described.
- 10 4. In an apparatus of the character described, the combination with a furnace having an opening in the front thereof for the admission of fuel above the grate, of an inclined chute adapted to receive the bagasse at its upper end from an elevated carrier and supported at said end in an elevated position; brackets secured to the front wall of the furnace and supporting the lower end of said chute; a portion of the floor of said chute being hinged and adapted to swing downward; ropes reeving over elevated pulleys and attached to said hinged portion for raising and lowering the same; a bladed roller mounted across the said chute near its lower end in bearings vertically movable in said brackets, and means for driving said bladed roller; a roller having radial teeth also mounted across said chute at its lower end in bearings vertically movable in said brackets; and gearing between said rollers for driving them in the same direction, substantially as described.
- 15 5. In an apparatus of the character described, the combination with a furnace having an opening in the front wall thereof for the admission of fuel; of an inclined chute adapted to receive the bagasse at its upper end from an elevated carrier, and supported at said end in an elevated position; brackets secured to the front of the furnace and supporting the lower end of said chute; the middle portion of the floor of said chute being hinged and adapted to swing downward; ropes reeving over elevated pulleys and attached to said hinged portion for raising and lowering the same; a bladed roller mounted across the said chute near its lower end in bearings vertically movable in said brackets, and means for driving said bladed roller; a toothed roller also mounted across said chute at its lower end in bearings vertically movable in said brackets; gearing between said rollers for driving them in the same direction; and a door pivoted to the front of the furnace above the fuel-opening and extending over said rollers and adapted to rise and fall with said bladed roller, substantially as described.
- 20 6. In an apparatus of the character described, the combination with a furnace having an opening in its front wall above the fire-grate, and an elevated carrier driven from any suitable source of power and running over an elevated drum, and a sprocket-gear mounted upon the shaft of said drum; of an inclined chute having its upper end supported beneath said drum; brackets secured to the front wall of the furnace and supporting the lower end of said chute in front of the fuel-opening therein; a bladed roller mounted across said chute near its lower end in vertically-movable bearings in said brackets, and means for driving said bladed roller; a roller having radial teeth also mounted across said chute at its lower end in bearings vertically movable in said brackets; and gearing between said rollers for driving them in the same direction; and a door pivoted to the front of the furnace above the fuel-opening and adapted to rise and fall with said bladed roller, substantially as described.
- 25 7. In an apparatus of the character described, the combination with a furnace having an opening in its front wall above the fire-grate, and an elevated carrier driven from any suitable source of power and running over an elevated drum, and a sprocket-gear mounted upon the shaft of said drum; of an inclined chute having its upper end supported beneath said drum; brackets secured to the front wall of the furnace and supporting the lower end of said chute in front of the fuel-opening therein; a bladed roller mounted across said chute near its lower end in vertically-movable bearings in said brackets, and means for driving said bladed roller; a roller having radial teeth also mounted across said chute at its lower end in bearings vertically movable in said brackets; and gearing between said rollers for driving them in the same direction; and a door pivoted to the front of the furnace above the fuel-opening and adapted to rise and fall with said bladed roller, substantially as described.
- 30 8. In an apparatus of the character described, the combination with a furnace having an opening in its front wall above the fire-grate, and an elevated carrier driven from any suitable source of power and running over an elevated drum, and a sprocket-gear mounted upon the shaft of said drum; of an inclined chute having its upper end supported beneath said drum; brackets secured to the front wall of the furnace and supporting the lower end of said chute in front of the fuel-opening therein; the middle portion of the floor of said chute being hinged and adapted to swing downward; ropes reeving over elevated pulleys and attached to said hinged portion for raising and lowering the same; a bladed roller mounted across said chute near its lower end in vertically-movable bearings in said brackets, and having a sprocket-gear on the shaft thereof; a sprocket-chain passing over said sprocket-gear and over the sprocket-gear on the shaft of said drum, and driven by the latter; a toothed roller also mounted across said chute, immediately in front of the furnace-opening in bearings ver-

5 tically movable in said brackets; gearing be-
tween said rollers whereby the two are driven
in the same direction; and a door pivoted to
the front of the furnace above the fuel-open-
ing and adapted to extend over said rollers
and normally rest upon said bladed roller,
substantially as described.

9. In an apparatus of the character de-
scribed, the combination with a furnace, hav-
10 ing an opening in its front wall above the fire-
grate, and a carrier driven by any suitable
source of power and running over an elevated
drum, and a sprocket-gear mounted upon the
shaft of said drum; of an inclined chute hav-
15 ing its upper end supported beneath said
drum; brackets secured to the front wall of
the furnace and supporting the lower end of
said chute in front of the fuel-opening therein;
vertical bifurcated standards on said brack-
20 ets; vertically-movable journal-blocks mount-
ed in said bifurcated standards; a bladed
roller mounted across said chute near its lower
end in one pair of said journal-blocks, and
having a sprocket-gear on the shaft thereof;
25 a sprocket-chain meshing with said sprocket-
gear and the sprocket-gear on the shaft of
said drum and driven by the latter; a toothed
roller also mounted across said chute imme-
diately in front of the furnace-opening in an-
30 other pair of said journal-blocks; gearing be-
tween said rollers whereby the two are driven
in the same direction; and a metallic door
pivoted to the front of the furnace above the
fuel-opening, and extending over both of said
35 rollers and adapted to rise and fall with said
bladed roller, substantially as described.

10. In an apparatus of the character de-
scribed, the combination with a furnace, hav-
40 ing an opening in its front wall above the fire-
grate, and an elevated carrier driven from
any suitable source of power running over an
elevated drum, and a sprocket-gear mounted
upon the shaft of said drum; of an inclined
45 chute having its upper end supported beneath
said drum; brackets secured to the front wall
of the furnace and supporting the lower end
of said chute in front of the fuel-opening
therein; the middle portion of the said chute
being hinged and adapted to swing downward;
50 means for raising and lowering said hinged
portion; brackets secured to the front wall
of the furnace and supporting the lower end
of said chute in front of the fuel-opening
therein; vertical bifurcated standards on said
55 brackets; vertically-movable journal-blocks
mounted in said bifurcated standards; a
bladed roller mounted across said chute near
its lower end in one pair of said journal-
blocks, and having a sprocket-gear on the

60 shaft thereof; a sprocket-chain meshing with
said sprocket-gear and the sprocket-gear on
the shaft of said drum and driven by the lat-
ter; a toothed roller also mounted across said
chute immediately in front of the furnace-
65 opening in another pair of said journal-blocks; 65
gearing between said rollers whereby the two
are driven in the same direction; and a me-
tallic door pivoted to the front of the furnace
above the fuel-opening, extending entirely
70 across said chute between the sides thereof
above said rollers, and adapted to rise and
fall with said bladed roller, substantially as
described.

11. In an apparatus for feeding bagasse to
furnaces, the combination with an inclined 75
chute provided with raised sides and sup-
ported at its lower end by brackets secured
to the wall of the furnace; a toothed roller
mounted in vertically - movable bearings
across the lower end of said chute; a bladed 80
roller for feeding the bagasse to the said
toothed roller also mounted in vertically-
movable bearings across the lower end of said
chute; means for driving said rollers; a me-
tallic door hinged to the front of the furnace 85
above the fire-door and between the sides of
said chute and extending over said rollers,
and supports for the outer end of said hinged
door, adapted to rise and fall with said bladed
90 roller, substantially as described. 90

12. In an apparatus for feeding bagasse to
furnaces, the combination with an inclined
chute provided with raised sides and sup-
ported at its lower end by brackets secured
to the wall of the furnace; a toothed roller 95
mounted in vertically - movable bearings
across the lower end of said chute, and adapt-
ed to throw the bagasse off therefrom over
the grate-bars of the furnace; a bladed roller
also mounted in vertical movable bearings 100
across the lower end of said chute; means for
driving said rollers; slotted plates mounted
in guides upon the sides of said chute and
belting over the shafts of said rollers, and
adapted to rise and fall therewith; lugs ex- 105
tending inwardly from said plates; and a
metallic door hinged to the front wall of the
furnace above the fire-door thereof, fitting
between the sides of said chute and extend-
ing over said rollers and resting at its outer 110
end upon said lugs, substantially as described.

In testimony whereof I affix my signature
in presence of two witnesses.

JAMES FISHER.
